METHOD OF REFINING VEGETABLE OILS
IN MISCELLA

John A. Ziegler, Toronto, Ontario, Canada, assignor to Canadian Breweries Limited, Toronto, Ontario, Canada, a corporation of Ontario

No Drawing. Application September 28, 1950,
Serial No. 187,353

5 Claims. (Cl. 260—426)

1

This invention relates to a process for refining vegetable oils in miscella.

Vegetable oils are usually extracted from the source material either by cold or hot pressing, or by solvent extraction (such as hexane) followed by removal, through distillation, of the solvent. In each case a crude oil results. Conventional treatment of this crude oil begins with a degumming step in which gums, resins, phosphatides, sterols and some waxes are precipitated from the oil after agitating it with 1 to 10% of water at temperatures from 70° F. to 150° F. for periods of up to 30 minutes, after which the gums are removed by centrifugation. The resulting oil is called a degummed oil but still contains coloured impurities and free fatty acids. These latter are removed in a second step involving agitating the oil with an aqueous solution of an alkali (commonly caustic soda) under very carefully controlled conditions until the soap which is formed precipitates out as a coarse curd which may be easily removed by filtration or centrifugation. This step requires a skilled operator in order to obtain a satisfactory "break" of the soap which ordinarily is formed as a finely divided suspension in the oil. The third step consists of mixing the degummed, alkali refined oil with a bleaching agent such as a suitable clay in an amount up to about 5% of the weight of the oil. The mixture is held at elevated temperatures, preferably in an inert atmosphere or even under a vacuum for between fifteen and thirty minutes, and then is filtered. The resulting oil is referred to as degummed, alkali refined, bleached oil. There are appreciable losses of oil due to mechanical occlusion at each step and the overall loss by the time the oil emerges from the bleach step may be as high as eight to ten per cent.

The use of the term "miscella" herein is intended to define a solution of a glyceride oil in an extracting solvent.

It is an object of the invention to reduce overall refining losses.

Another object of the invention is to produce more attractive by-products such as a very light coloured soap containing much less neutral oil and light coloured foots which are neutral.

A further object of the invention is to provide a process for refining vegetable oils in miscella wherein the oil is subjected to a milder treatment throughout than formerly, thus resulting in a higher tocopherol content than that obtainable by conventional processes.

A still further object of the invention is to provide a process for refining vegetable oils in

2

miscella wherein the degumming step is the last step and wherein only partial degumming may be employed to leave phosphatides in the oil to act as stabilizers.

5 Other objects of the invention will be appreciated by a study of the following specification.

The process of the invention is applied to a miscella which may contain up to twenty per cent dissolved vegetable oil. The solvent employed 10 may be hexane and it is desired that the miscella be received from the extractor at a temperature of about 150° F.

The first step of the process herein embodies the decolourizing of the hot miscella by means of 15 a decolourizing agent such as a suitable bleaching clay by mixing it either continuously or batchwise therewith in an amount up to 3% by weight of the oil in the miscella. Any suitable bleaching clay may be employed but with a bleaching 20 clay known by the trade-mark "Tonsil" the decolourizing may continue for about ninety seconds, after which the clay is removed by filtration and then the decolourized miscella may be pumped to an evaporator for partial removal of 25 the solvent so that the oil content in the miscella reaches about fifty per cent by weight. The usual bleaching clays may require a contact period of about 30 minutes.

The hot concentrated miscella is then mixed 30 either continuously or batchwise with an alkali refining agent such as sodium hydroxide or preferably a caustic brine of sodium chloride solution containing an amount of sodium hydroxide calculated to neutralize the free fatty acids. 35 The reaction is very rapid and the soaps precipitate out in about one minute, being removed centrifugally.

Other salts such as sodium nitrate and sodium sulphate, may be employed for alkali refining where the solutions of same contain an amount of sodium hydroxide for the purpose of neutralizing free fatty acids.

The alkali refined miscella concentrate is then subjected to distillation by which the solvent is 45 removed to leave a decolourized and alkali refined oil which still retains the phosphatides. The phosphatides may be removed in the conventional manner by treating the solvent-free oil with water and centrifuging. By varying the amount 50 of water and time of agitation, all or part of the phosphatides may be removed.

The phosphatides resulting are neutral and very light in colour and their neutrality considerably enhances their keeping qualities.

It has been found that the use of caustic brine

in the alkali refining step has an advantage over the use of caustic soda alone in that the brine renders the soap insoluble in the aqueous phase. The presence of the brine also enables the separation of the soap to occur more rapidly and, moreover, inhibits emulsification in the alkali refining step.

A modification of the process herein involves combining two steps in one, that is, alkali refining and degumming. This is accomplished merely by increasing the contact time of the alkali refining step using caustic brine. Thus, for example, if a soybean miscella is treated with caustic brine for a period of ten minutes or more rather than for a relatively short period of, say, one minute, degumming takes place along with alkali refining to produce what is called in the trade a "break-free oil."

In order to illustrate the process herein the following examples are presented.

Example 1

10 litres of soybean miscella of specific gravity 0.717 (obtained from the factory extractor) were warmed to 140° F. and agitated for 90 seconds with 40 grams of Tonsil AC (bleaching clay) and filtered. The filtrate was perfectly clear, golden yellow since much of the reddish colour had been removed. A sample of this filtrate when evaporated until free of solvent gave an oil of colour 5 (Gardner-Holt scale).

10 litres of such decolourized soybean miscella was evaporated until the specific gravity (68° F.) rose to 0.790 (oil content about 52% by weight). The concentrated miscella was rapidly stirred while still hot, with 300 ml. of a solution containing 3% sodium hydroxide and 8% sodium chloride for 2 minutes, then centrifuged. A three phase system resulted consisting of miscella on top, a middle layer of solid soap and a lower aqueous brine layer containing some colouring matter derived from the oil. The soap layer was nearly white and could be used as an excellent starting source of fatty acids by those industries so engaged. Upon evaporation of the hexane from the refined miscella, a clear golden yellow soybean oil having a free fatty acid content of 0.04% by weight resulted.

Example 2

1000 grams of oil resulting from Example 1 were stirred at 140° F. with 25 ml. water for 30 minutes then centrifuged. A clear break-free soybean oil resulted and the foots had a very light cream colour. A titration of the foots indicated that the free fatty acid content was also 0.04% and they were remarkably stable against deterioration when stored at room temperature.

Example 3

A concentrated miscella prepared according to the bleaching and concentrating steps of Example 1 to an oil content of 55% and in the amount of 1 litre was stirred rapidly with 50 ml. of a solution containing 3% sodium hydroxide and 5% sodium chloride for ten to fifteen minutes to illustrate a modified process herein having combined refining and degumming steps. Upon removal of the solvent from the miscella the resulting oil had a free fatty acid content of 0.02% and was found to be substantially degummed.

A sample of 20 litres soybean miscella treated in accordance with the process steps outlined in Examples 1 and 2 showed an overall refining loss of oil of 5.0%.

It will be observed that the present process

differs from prior processes of the same general character in that the steps are carried out in the presence of the extracting solvent and in substantially reverse order, resulting in lesser refining loss and more valuable by-products. Because of the presence of the solvent, less oil is in contact with the refining agent at any given moment, resulting in a greater yield of refined oil by reason of a reduction in refining losses. In addition, since comparatively low temperatures are employed throughout the process there is less chance for destruction of some of the labile anti-oxidants naturally present in the oil and hence the resulting refined oil has less tendency toward oxidative rancidity. Also by means of the present process the conditions may be adjusted so as to leave a trace of the phosphatides in the oil since the degumming step is performed after alkali refining. As a result a desired portion of the phosphatides may be retained to enhance the stability of the refined oil.

It is intended that the present disclosure should not be construed in any limiting sense apart from that indicated by the scope of the following claims.

What I claim as my invention is:

1. In a process for refining vegetable oils in hexane, the method of providing a refined vegetable oil containing bleached neutral phosphatides, comprising: decolourizing the vegetable oil while in hexane, then mixing the decolourized oil while in hexane, with an alkali refining agent containing only sufficient sodium hydroxide to neutralize the free fatty acids thereof but providing retention of the phosphatides in the oil; and separating out the neutralized free fatty acids into soaps with a brine while neutralizing said free fatty acids.

2. The method as claimed in claim 1, and the step of: extracting the bleached neutral phosphatides from the refined oil after removal of the hexane therefrom by distillation.

3. The method as claimed in claim 1 and the step of: extracting only a portion of the bleached neutral phosphatides remaining in the refined oil to permit the latter to retain a sufficient amount to act as a stabilizer.

4. The method of refining vegetable oils to obtain a refined vegetable oil containing bleached neutral phosphatides, comprising: forming a miscella of the vegetable oil in hexane; decolourizing the miscella with a decolouring agent; removing the said decolourizing agent; mixing the decolourized miscella with an alkali refining agent containing only sufficient sodium hydroxide to neutralize the free fatty acids thereof but providing retention of the phosphatides in the oil; extracting soap stock from the neutralized decolourized miscella; and thereafter removing the hexane from said miscella to provide said refined oil.

5. The method according to claim 4, and the step of: removing the bleached neutral phosphatides from the oil after the hexane has been removed therefrom.

JOHN A. ZIEGLER.
